UNITED STATES PATENT OFFICE.

WILLIAM F. YARYAN AND LOUIE H. CHAMBERLAIN, OF CLARINDA, IOWA.

SNAP-FLASK JACKET.

1,253,920.

Specification of Letters Patent. Patented Jan. 15, 1918.

Application filed March 2, 1917. Serial No. 152,100.

To all whom it may concern:

Be it known that we, WILLIAM F. YARYAN and LOUIE H. CHAMBERLAIN, citizens of the United States, residing at Clarinda, in the 5 county of Page, and State of Iowa, have invented new and useful Improvements in Snap-Flask Jackets, of which the following is a specification.

This invention is an improved foldable 10 and extensible snap flask jacket for use on molds, in casting, the object of the invention being to provide an improved snap flask jacket which may be adjusted to fit molds of various sizes and shapes, whether 15 of oblong rectangular form, trapezoidal or rhomboidal and to also fit molds which taper in one direction; another object being to provide an improved snap flask jacket which when not in use may be compactly folded 20 and arranged on a shelf or other support out of the way, and to take up but very little room.

With the above and other objects in view the invention consists in the construction, 25 combination and arrangement of devices hereinafter described and claimed.

In the accompanying drawings:—

Figure 1 is a perspective view of a snap flask jacket constructed in accordance with 30 our invention and as extended and arranged for use on a mold of oblong rectangular form.

Fig. 2 is a detailed perspective view of one corner of the snap flask jacket as arranged to fit on a mold which tapers in one direction and is smaller at the upper side than at the lower side.

Fig. 3 is a longitudinal sectional view of our improved snap flask jacket, showing the 40 same compactly folded and as adapted to be placed on a shelf or other support and arranged out of the way.

Fig. 4 is a detailed sectional view through one side of the snap flask jacket.

Fig. 5 is a detailed sectional perspective view of one of the hinges which connect the side and end walls of the jacket at the corners of the jacket and adapt said side and end walls to be folded or to be arranged at 50 any desired angle according to the shape of the mold.

Fig. 5^a is a detail elevation of one of the hinge bars.

Fig. 6 is a detailed perspective view of 55 one of the extension plates.

Fig. 7 is a detailed perspective view with

parts broken away showing a modified construction of the snap flask jacket.

Fig. 8 is a detailed sectional view of the same. 60

Our improved snap flask jacket comprises side walls 1, end walls 2 and universal joint hinges 3 which connect the side and end walls together at the corners of the jacket. Each side wall comprises a pair of plates 4, 65 5, of iron, steel or any other suitable material and which plates are provided respectively with outstanding upper and lower rims or flanges 6, 7. The width of each plate 5 is slightly less than that of the plate 4 so that the said plates may be arranged in overlapping relation and with the flanges of the plate 5 engaging the inner surfaces of the flanges 6 of the plate 4 so that said flanges of the plates coact to hold the plates 70 75 in line with each other and also assist in guiding the plates and enabling them to be moved longitudinally with relation to each other to shortened or extended sides as may be required by the size of the mold on which 80 the jacket is to be used.

Each end wall 2 also comprises a pair of plates 8, 9 of iron, steel or other suitable material and which are similar in construction to the plates of the side walls, said 85 plates 8, 9 being respectively provided with out-turned upper and lower flanges 10, 11 and said plates being arranged in over-lapping relation and for relative sliding movement so that the length of each end wall 90 may be extended or diminished as required by the size of the mold. Each plate 5 has a longitudinal slot 12 engaged by a clamping bolt 13 with which each plate 4 is provided each clamping bolt having a washer 14 which 95 bears on the outer side of the plate 5 and being also provided with a wing or thumb nut 15. Hence the plates 4, 5 may be clamped together and secured at any desired 100 adjustment of the side walls as will be understood. Each plate 9 of each end wall has a similar slot 16 engaged by a bolt 17 with which the companion plate 8 is provided, each of said bolts having a washer 18 and a clamping or thumb nut 19. Hence the 105 plates or members of the end walls may also be clamped together at any desired extension or adjustment of the end walls as will be understood.

The ends of the side and end walls of the 110 snap flask jacket are connected together at the corners of said jacket by the universal

hinges 3 each of which comprises a pair of bars 20, 21 secured on the said side and end walls or the plates thereof at points near their contiguous ends. The bar 20 of each hinge is integral and is rigidly secured in place by rivets 22. Said bar is provided at its center, on its outer side, with an arm 23 which is provided with a ball 24. Each hinge bar 21 comprises a rigidly secured member 25 and an adjustably secured member 26 the member 25 being secured on the plate of one of the walls by rivets 27 and the member 26 being provided with adjusting slots 28 engaged by clamping bolts 29 which have washers 30 and winged or thumb nuts 31. Said slots and clamping bolts permit the member 26 to be adjusted toward and from the member 25. Said members are arranged with their opposed ends in spaced relation and are provided at their opposed ends with out-turned ears 32. Segmental socket recesses 33 are formed in said ears for the reception of the ball 24 so that a ball and socket joint is formed between the members of each hinge and the hinge members are thereby adapted for universal movement so that the side and end walls of the snap flask jacket may be arranged at right-angles to each other or at any desired angle and may be also arranged closer together at the top or bottom than at the opposite extremity and hence the snap flask jacket may be adapted to fit a mold of any shape whether rectangular or rhomboidal and may be also adapted to fit a mold which tapers in one direction. The ears 32 are connected together by a bolt 34 which may be adjusted to secure any desired grip or tension between the bolt and socket members of the hinges and to prevent lost motion. In practice the hinge members are preferably of malleable material.

It will be observed that owing to the provision of the arms 23 on the hinge bars 20 and the provision of the ears 32 on the hinge bars 21 the hinges serve to hold the ends of the side and end walls in spaced relation or open at the corners of the jacket to adapt said side and end walls to be adjusted to any desired angle, according to the shape of the mold on which the jacket is to be used, and to also adapt the side and end walls of the jacket to be folded compactly as shown in Fig. 3.

We also provide extension plates 35 of suitable length for use on the inner sides of the slotted plates of the side and end walls or either of them, to cover the slots and extend from the unslotted plate to the outer end of the slotted plate so that any side or end wall may be arranged, when extended, with an unbroken inner surface to bear one side of the mold. The extension plates correspond cross-sectionally with the slotted plates of the side and end walls, are made

of steel, iron or any other suitable material and are provided with flanges 36.

In Fig. 7 of the drawings we show a modified construction of the snap flask jacket in which the use of the extension plates and the provision of the slots in certain of the plates of the end and side walls of the jacket may be dispensed with. In this modified construction the inner end edges of the plates 4 or 8 are beveled or ground to an edge as at 37 on the side next to the mold and the coengaging out-turned flanges of the plates of the side and end walls are secured together at any desired adjustment by thumb screws 38.

By first loosening the bolts 29 and the bolts 34 the ball members of the hinges may be disconnected from the socket members to permit the separation and detachment of the side and end walls of the jacket as will be understood.

While we have herein shown and described a preferred form of our invention we would have it understood that changes may be made in the form, proportion and construction of the several parts, without departing from the spirit of our invention and within the scope of the appended claims.

Having thus described the invention, what we claim is:

1. A snap flask jacket of the class described comprising side and end walls and connections between said walls at the corners of the jacket, said connections embodying universal joints adapting said walls for universal angular movement, to enable the jacket to be folded and to be also used on molds of various shapes, said side and end walls being longitudinally extensible and each comprising a pair of plates arranged in over-lapping relation, the outer plates having slots, and bolts connecting said plates together and extending through said slots, said side and end walls also comprising extension plates on the inner sides of and covering the slots of said outer plates.

2. A snap flask jacket of the class described comprising side and end walls and hinges forming connections between said side and end walls at the corners of the jacket, each hinge comprising a pair of bar members one having an arm provided with a ball and the other having a socket in which the ball is mounted for universal angular movement, said arms causing the hinge members to hold the side and end walls in spaced relation at the ends of said side walls and corners of the jacket.

3. A snap flask jacket of the class described comprising side and end walls and hinges forming connections between said side and end walls at the corners of the jacket, each hinge comprising a pair of bar members one having an arm provided with a ball and the other having a socket

in which the ball is mounted for universal angular movement, said arms causing the hinge members to hold the side and end walls in spaced relation at the ends of said side walls and corners of the jacket, each socket bar comprising a pair of members adapted for relative adjustment and provided with means to adjust and secure said members and thereby enable any desired tension to be secured at the ball and socket joint.

In testimony whereof we affix our signatures.

WILLIAM F. YARYAN.
LOUIE H. CHAMBERLAIN.
